WATER TUBE BOILER

Adalbert Schmidli, Winterthur, Switzerland, assignor to the Firm Sulzer Frères Société Anonyme, Winterthur, Switzerland

Application August 18, 1931, Serial No. 557,828,
and in Switzerland and Germany August 19,
1930

5 Claims. (Cl. 122—302)

This invention relates to water tube boilers of the kind comprising a lower drum communicating with each of two or more upper drums through upflow and downflow tubes arranged vertically or at a steep angle to the horizontal.

Boilers of this type have been open to the disadvantage that under certain conditions of load and heat supply reversal of the circulation of the working medium tends to take place and local circulation is liable to occur in the nests of tubes thereby impairing efficient circulation of the fluid.

According to the present invention not only do some at least of the upflow tubes from the lower drum open into the steam space of one upper drum which communicates with the lower drum through downflow tubes, but also some at least of the upflow tubes from the same lower drum open into the steam space of the second upper drum whose water space communicates in known manner with the lower drum through downflow tubes, so that when the boiler is steaming at a high rate, the rate of evaporation from the surface of the water in the upper drums is kept low and circulation through the tubes in the same direction is ensured.

One construction of boiler according to the invention is illustrated by way of example in the accompanying drawing and comprises a lower drum 1, and two upper drums 2 and 3. The lower drum 1 communicates with the upper drum 2 through upflow tubes 4 some of which open into the steam space 5 whilst the remainder open into the water space as shown. The drum 2 also communicates with the lower drum 1 through downflow tubes 6 which are protected from the direct action of the hot gases by walls 7.

The lower drum is similarly in communication with the upper drum 3 through upflow tubes 8 some of which open into the steam space 9 and the remainder into the space normally occupied by water. The upper drum 3 in addition communicates with the lower drum through downflow tubes 10, baffle plates 11 and 12 being provided adjacent to the tubes 8 and 10 respectively.

The steam spaces 5 and 9 of the drums 2, 3 communicate through tubes 13, the water spaces of these two upper drums communicating through tubes 14. Walls 15 and 16 are provided for the purpose of protecting the upper parts of the tubes from the direct action of the hot gases, additional tubes 17 being arranged below the wall 16 and serving as additional communication between the water spaces of the drums 2, 3.

An additional baffle plate 18 is arranged as

shown adjacent to the inner tubes 4 and super-heating tubes 19 are disposed in the space between the baffle plate 18 and additional upflow tubes 20 communicating between the lower drum 1 and the upper drum 2 and disposed adjacent to one of the protecting walls 7. The super-heater 19 communicates with the steam space 9 of the upper drum 3 through a pipe 21, a pipe 22 conducting the steam to the point of consumption.

The circulation of the working medium is indicated by the arrows shown in full lines and the path followed by the combustion gases is indicated by the arrows shown in chain lines from which it will be seen that circulation of the medium between the lower drum 4 and each of the upper drums 2 and 3 takes place in one direction only and that greater part of the down flow tubes 6 is protected from the direct action of the hot gases not only by the walls 7 but in addition by the upflow tubes 20.

It will be understood that while the invention has been described as applied to a boiler having one lower drum and two upper drums several such arrangements may be employed in combination, efficient water circulation being ensured by the fact that each individual system of tubes, i. e. upflow and downflow, is always traversed by the working medium in one and the same direction.

1 claim:—

1. Vertical water-tube boiler comprising at least two upper drums belonging to a joint lower drum and partly filled with water, characterized in that the upflow tubes leading from the lower drum to the upper drums terminate partly in the steam space of the upper drums, and that downflow tubes are provided leading from every upper drum to the lower drum and situated behind the upflow tubes of the respective upper drum, the downflow tubes situated in front of the upflow tubes of the second upper drum being shielded from the action of flue gases by being insulated on the side of the upper drum.

2. In a water tube boiler, in combination a furnace, a lower drum, a plurality of upper drums, one in front of the other, upflow tubes connecting said lower drum to each of said upper drums, some at least of said upflow tubes leading to each upper drum opening into the steam spaces of said upper drums, downflow tubes connecting the water space of each of said upper drums to said lower drum, walls extending from the front upper drum and surrounding the greater part of the length of said downflow tubes lying nearer

said furnace and serving to protect said tubes from direct action of the hot gases of said furnace, tubes connecting the steam spaces of said upper drums and tubes connecting the water spaces of said upper drums.

3. In a water tube boiler, in combination a furnace, a lower drum, a plurality of upper drums, one in front of the other, upflow tubes connecting said lower drum to each of said upper drums, some at least of said upflow tubes leading to each upper drum opening into the steam spaces of said upper drums, downflow tubes connecting the water space of each of said upper drums to said lower drum, walls extending from the front upper drum and surrounding the greater part of the length of said downflow tubes lying nearer said furnace and serving to protect said tubes from direct action of the hot gases of said furnace, a baffle plate between said protected downflow tubes and said upflow tubes lying nearer said furnace, a second baffle plate between said upflow tubes lying further away from said furnace and said downflow tubes furthest away from said furnace, a third baffle plate behind said downflow tubes lying furthest away from said furnace, tubes connecting the steam spaces of said upper drums, tubes connecting the water spaces of said upper drums, and a baffle plate beneath said tubes connecting the water spaces of said upper drums.

4. In a water tube boiler, in combination a
furnace, a lower drum, a plurality of upper
drums, one in front of the other, upflow tubes
35 connecting said lower drum to each of said upper
drums, some at least of said upflow tubes lead-
ing to each upper drum opening into the steam
spaces of said upper drums, downflow tubes con-
necting the water space of each of said upper
40 drums to said lower drum, walls extending from
the front upper drum and surrounding the greater
part of the length of said downflow tubes
lying nearer said furnace and serving to protect
said tubes from direct action of the hot gases of
45 said furnace, a baffle plate between said protect-
ed downflow tubes and said upflow tubes lying
nearer said furnace, super-heater tubes arranged

between said baffle plate and said protected down-flow tubes, a tube connecting said super-heater tubes to one of said upper drums, a second baffle plate between said upflow tubes lying further away from said furnace and said downflow tubes 80 furthest away from said furnace, a third baffle plate behind said downflow tubes lying furthest away from said furnace, tubes connecting the steam spaces of said upper drums, tubes connecting the water spaces of said upper drums and a 85 baffle plate beneath said tubes connecting the water spaces of said upper drums.

5. In a water tube boiler, in combination a
furnace, a lower drum, a plurality of upper drums,
one in front of the other, upflow tubes connect-
ing said lower drum to each of said upper drums,
some at least of said upflow tubes leading to each
upper drum opening into the steam spaces of
said upper drums, downflow tubes connecting the
water space of each of said upper drums to
said lower drum, walls extending from the front
upper drum and surrounding the greater part of
the length of said downflow tubes lying nearer
said furnace and serving to protect said tubes 100
from direct action of the hot gases of said fur-
nace, a baffle plate between said protected down-
flow tubes and said upflow tubes lying nearer
said furnace, superheater tubes arranged be-
tween said baffle plate and said protected down-
flow tubes, additional upflow tubes between said 105
protected downflow tubes and said super-heater
tubes, a tube connecting said super-heater tubes
to one of said upper drums, a second baffle plate
between said upflow tubes lying further away 110
from said furnace and said down-flow tubes fur-
thest away from said furnace, a third baffle plate
behind said downflow tubes lying furthest away
from said furnace, tubes connecting the steam
spaces of said upper drums, tubes connecting the 115
water spaces of said upper drums, a baffle plate
beneath said tubes connecting the water spaces
of said upper drums and additional tubes be-
neath said last mentioned baffle plates connect-
ing the water spaces of said upper drums 120
